UNITED STATES PATENT OFFICE.

ROBERT NEUEDER, HOLLYWOOD, ILLINOIS, ASSIGNOR TO BEARDSLEE CHANDELIER MANUFACTURING COMPANY, OF CHICAGO, ILLINOIS, A CORPORATION OF DELAWARE.

DESIGN FOR A BOWL FOR LIGHTING-FIXTURES.

53,342.

Specification for Design.

Patented May 20, 1919.

Application filed February 24, 1919. Serial No. 278,993. Term of patent 7 years.

To all whom it may concern:

Be it known that I, ROBERT NEUEDER, a citizen of the United States, residing at Hollywood, in the county of Cook and State of Illinois, have invented a new, original, and ornamental Design for a Bowl for Lighting-Fixtures, of which the following is a specification, reference being had to the accompanying drawing, which forms a part hereof.

My invention, in its specific exemplification, has been illustrated applied to a bowl for lighting fixtures, whether of glass or other suitable material; it being understood, however, that my improved design may be

applied to other parts or units of lighting fixtures, as for example, shades, shells and the like.

In the drawing:—

Figure 1 is a side elevation of a lighting fixture bowl provided with my new design.

Fig. 2 is a bottom plan view of the bowl shown in Fig. 1.

I claim:—

The ornamental design for a bowl for lighting fixtures as shown.

ROBERT NEUEDER.
